UNITED STATES PATENT OFFICE

CHASE KEITH PEVEAR, OF NEW YORK, N. Y.

CRANE

Application filed February 9, 1928. Serial No. 252,958.

This invention relates to traveling cranes of the type in which a hoisting hook is suspended from a carriage running on overhead tracks.

Heretofore, it has been the practice in using large cranes to provide accommodations for the operator in a cab on the carriage and to lead the controls to that point so that the transverse movement of the carriage and the vertical movement of the hoisting hook have been controlled from the overhead cab. In using such a crane, the operator is necessarily confined at all times to this cab and it is necessary to provide a second operator to attend to the securing of the load to the hoisting hook and the disengagement of the load when it has been carried to its destination. The vertical movement of the hook and the transverse movement of the carriage are brought about by the operator in the overhead cab in response to signals given him by the operator on the floor who attends to the hoisting hook.

The present invention, in one aspect, consists in a traveling crane in which the controlling devices are located adjacent to the hoisting hook and accommodation for an operator is provided at that point. This not only eliminates the necessity of a crew of two operators for the crane but increases its capacity and adapts it for use in new and advantageous ways. For example, since the path and location of the hoisting hook are the main considerations in the operation of the crane, it will be apparent that an operator riding upon the hook and having the controls at his command will be able to direct the movements of the hook more accurately and more rapidly than when these are determined by signals relayed to an operator in an overhead cab.

In a crane constructed in accordance with my invention, I preferably provide a small cab located just above the hook and containing the controls and accommodation for the operator. He is thus enabled to step out of his cab to place the tackle or slings on the load to be lifted. When he has secured his load, he steps into his cab and rides with the load to its destination. This may be on

top of a high pile where it would be difficult for a man to climb. Similarly, with a crane constructed in accordance with my invention, it is possible to dig out a pile of boxes twenty or thirty feet high surrounded entirely by other material, in which case the hoisting hook would be operating in a space not more than four feet square and perhaps twenty or thirty feet deep.

The capacity of a warehouse equipped with such a crane is largely increased as compared with that served by cranes as heretofore constructed, in that the material may be piled as high as the space under the crane will permit without the necessity of allowing space for aisles. Such a crane, moreover, may be used for hoisting material from a warehouse through hatchways in floors above, a procedure which has not heretofore been practical.

A feature of construction useful in connection with the crane of my invention consists in a swivel hoisting hook secured to a transversely extending plate located in position where it may be conveniently turned by the operator in the cab. This plate is herein shown as forming a part of the cab floor where the operator may turn it with his feet and so swing his load into the position required for landing while in transit.

These and other features of the invention will be best understood and appreciated from the following description of a preferred embodiment thereof, selected for purposes of illustration and shown in the accompanying drawing, in which

Fig. 1 is a view in elevation of the crane, sections being broken out of the overhead beam;

Fig. 2 is a view in front elevation on a larger scale of the cab and hoisting hook; and

Fig. 3 is a similar view in side elevation.

The crane comprises an overhead beam 10, having flanged rollers 12 at either end which run on tracks 13, supported by I-beams 14 which are incorporated in the permanent structure of the walls of the warehouse served by the crane. The beam 10 comprises two sections, separated by a substantial space, and has upon its upper surface tracks 16 upon

which is mounted, for movement longitudinally of the beam, the carriage 18. The carriage 18 is supported by flanged rollers 20 and includes a hoisting drum 22 and motors for traction and hoisting, which are indicated diagrammatically and which may be of any well known commercial type.

Suspended from the carriage 18 by a pair of cables 38 is the hoisting hook 42 and a cab 10 for the operator. The cab comprises a pair of vertical side beams 30, connected by a pair of upper cross girts 32 and a pair of lower cross girts 34. The upper cross girts 32 carry a pair of sheaves 36, over which run the cables 38 for hoisting the cab and the hook. The lower cross girts 34 carry a transverse bar 40, having a central opening for the shank of the hook 42 which is supported thereon by a thrust washer 46 and nut 47, so that it may 70 swivel freely with its load. Secured to the upper end of the shank of the hook 42 is a flat plate 48, perforated for lightness and adapted to be turned by the operator to swing the hook and its load into any desired angular 75 position. The perforations through the plate 48 also serve the purpose of affording the operator a better vision of and for operating the hook 42.

The body of the cab, wherein is the operator's station, is contained between the side beams 30 and is provided with a seat 50 for the operator and with a step 52 by which he may conveniently enter and leave the cab. The bottom of the cab is open above the plate 48, thus permitting the operator to reach the plate with his feet when he desires to swing the hook in positioning it for a load.

It will be understood that the overhead beam 10 is provided with a motor, not shown, 40 for driving the rollers 12 to cause the crane to travel bodily upon the tracks 13. The carriage 18, as already noted, is provided with a motor for driving the rollers 20 to cause the carriage to move longitudinally upon the overhead beam 10 and with a second motor for hoisting or lowering the cab. Electric controlling devices for all three of these motors are located in the cab in convenient reach of the operator, so that without leaving his seat he may cause the overhead beam to travel from one end of the warehouse to the other, the carriage to travel from one end of the beam 10 to the other and the cab to move vertically from its highest position adjacent to the carriage, as shown in Fig. 1, to the floor of the warehouse.

The construction of these controlling devices is not important as the requirements are served by any commercial form of apparatus. 60 As herein shown, a controller 60, having an operating handle 62, is located at the right hand of the operator and immediately in front of him. This controller is wired to the hoisting motor in the carriage 18 and thus governs the vertical movement of the cab. A

controller 64, having an operating handle 66, is located also at the right hand of the operator and above the controller 60 but within convenient reach. This is wired to the traction motor in the bridge beam 10 and, by manipulating the handle 66, this may be set in motion in either direction or brought to rest, as desired. A controller 68, having an operating handle 70, also disposed within convenient reach of the operator, is located adjacent to the controller 64 and is wired to the traction motor of the carriage 18, serving to control that motor in the movement of the carriage upon the bridge beam 10. The leads from all the controllers are collected and carried out from the cab through the flexible conduit 72 and extend in a flexible cable 74 to a hoisting drum 76 in the carriage 18. The flexible cable 74 is wound upon this drum simultaneously as the cab is elevated and paid out as the cab is lowered, and electrical connections are maintained at all times between the controllers and their respective motors.

In addition to providing means by which the operator may ride in a position adjacent to the hoisting hook, the cab serves also to protect the operator as the cab is raised and lowered and swung in various directions from being brought into contact with the walls of the warehouse or with piles of material. It will also be noted, as illustrated in Fig. 1, that the cab is of such width that it may pass between the two girders of the beam 10.

When the operator has brought the cab to the load he desires to hoist, he steps out of it and passes the slings or tackle about the load. He then resumes his seat in the cab and, by manipulating the controllers, elevates himself with the load and moves transversely to the desired destination. In landing the load, he may turn the plate 48 to secure the desired angular position thereof. When the load is landed, he leaves the cab, removes the slings or tackle from the load and hangs them upon the small hooks 90 provided on the walls of the cab for that purpose.

A landing stage 80 is shown in Fig. 1, by which the operator may leave the cab of the crane after the latter has been brought to an out-of-the-way position in the warehouse.

Reference is made herein to a hoisting hook but it will be understood that an eye, stud or any member to which hoisting slings or tackle may be secured would serve as well and is within the scope of the invention.

Having thus described my invention, what I claim as new and desire to secure by Letters Patent is:

1. In a traveling crane, a carriage movable upon overhead tracks, an operator's cab suspended on cables from the carriage, power means for driving the carriage on its tracks and for elevating the cab by said cables, means including controls in the cab and flexible cable connections to the carriage for

controlling the power means, a load-supporting element swivelled to and depending from the bottom of the cab, a plate located in the bottom of the cab in position to be engaged by the operator's feet, and means connecting the element and plate whereby the operator may swivel the element.

2. A traveling crane operator's cab adapted to be suspended on cables from the crane carriage and comprising a pair of spaced side beams providing cab space for the operator therebetween, means connecting the top ends of the beams and providing an anchoring connection for said cables, means connecting the bottom ends of the beams, a load-supporting element hung from the bottom of said last-named means in a position beneath the operator's station, and crane-controlling means within the cab.

26 3. In a traveling crane having a carriage movable upon overhead tracks and hoisting cables connected thereto, a narrow and compact operator's cab adapted to be suspended on said cables, means within the cab for controlling the raising and lowering thereof, a rotatable hoisting hook suspended beneath the cab, and a plate connected to the hook and accessible to the operator through the floor of the cab, whereby the cab with its hook is adapted to be lowered into deep confined spaces and engage and elevate loads therefrom.

4. In a traveling crane, a carriage movable upon overhead tracks, an operator's cab suspended on cables from the carriage, power means for driving the carriage on its tracks and for elevating the cab by said cables, means including controls in the cab and flexible cable connections to the carriage for controlling the power means, a load-supporting element hung from the bottom of the cab, and a perforated plate in the bottom of the cab and connected to said element whereby the operator can manipulate the element with his feet, the perforations in the plate permitting the operator a view of said element.

5. In a traveling crane a carriage movable upon overhead tracks, an operator's cab suspended on cables from the carriage and comprising spaced vertical side beams providing cab space for the operator therebetween and transverse members connecting the side beams above and below the operator's station, a hoisting hook rotatably supported by and beneath the lowermost transverse member substantially in vertical alignment with said cables, and operating means secured to the hook and located above said transverse member within reach of the operator in the cab.

6. In a traveling crane a carriage movable upon overhead tracks, an operator's cab suspended on cables from the carriage and comprising spaced vertical side beams providing cab space for the operator therebetween and

transverse members connecting the side beams above and below the operator's station, a hoisting hook rotatably supported by and beneath the lowermost transverse member, and operating means within reach of the operator in the cab for controlling the angular position of the hook without requiring him to leave the cab.
